UNITED STATES PATENT OFFICE.

RICHARD S. KELLY, OF JERSEY CITY, NEW JERSEY.

WINDOW SASH.

Application filed March 10, 1928. Serial No. 260,629.

This invention relates to new and useful improvements in window sashes and aims to provide a stationary sash structure for disposition within the usual wall frame and where-
 5 in the same includes a plurality of horizontal glass panels or panes, mounted at their ends for turning movement. Normally, the opposite longitudinal edges of these glass panels are in overlapping relation whereas means
 10 is provided for permitting of the simultaneous turning of all the panels upon their axes so that the room may be properly ventilated.

An important object of this invention re-
 15 sides in the provision of a window sash of this character that is of very simple construction when considering the advantages there-
 of, and wherein the various glass panels may be easily replaced when broken, thus over-
 20 coming the requirement of the replacing of a large glass panel now employed in sliding and swinging sashes.

Furthermore, the use of a sash of this character will permit of the proper ventilation of
 25 the room when the panels are moved to open position, and this without any liability of draft or without any possibility of rain, snow and the like passing between said panels.

With the foregoing and other objects in view as the nature of the invention is better understood the same comprises the novel form, combination and arrangement of parts hereinafter more fully described, shown in
 35 the accompanying drawings and claimed.

In the drawings wherein like reference characters indicate corresponding parts throughout the several views:

Figure 1 is an inside elevation of my im-
 40 proved sash arranged within a window frame.

Figure 2 is an enlarged fragmentary horizontal section taken substantially upon the line 2-2 of Figure 1 and looking downwardly in the direction of the arrows.

Figure 3 is an enlarged fragmentary vertical section through the rockably mounted glass panel looking toward one vertical edge of the sash frame disclosing the means whereby the ends of the panels are rotatably mounted within the frame.

Figure 4 is an inside perspective of one of the circular rotating members within which the opposite ends of the glass panels are arranged.

Figure 5 is an outside perspective thereof.

Figure 6 is a fragmentary vertical section through the upper end of the sash structure.

Figure 7 is a fragmentary vertical section and inside perspective of one of the side frame members of the sash.

Figure 8 is a broken inner perspective of the main panel control lever.

Figure 9 is a fragmentary perspective of the upper horizontal stop bar for the upper-
 65 most glass panel.

Figure 10 is a detail vertical section through one vertical side of the frame structure, this view being taken substantially upon the line 10-10 of Figure 2.

Figure 11 is a perspective of one of the glass panels, and

Figure 12 is an enlarged transverse section taken substantially upon the broken line
 75 12-12 of Figure 3.

Now having particular reference to the drawings, A in Figure 1 consists of a generally conventional wooden frame structure for disposition or arrangement within the building wall during the construction thereof.

The present invention per se consists of a pair of vertical frame units B-B for disposition against the inner sides of the vertical frame members of the window frame A. Each unit B consists of a backing strip 5 the rear vertical edge of which is formed with a relatively wide inwardly extending flange 6, while the forward vertical edge thereof is formed with a relatively narrow inwardly extending flange 7. Arranged against the strip 5 and between the flanges 6 and 7 is a channel strip 8, said strips 5 and 8 being formed intermediate their vertical edges with spaced registering openings whereby the strip may be tightly secured together and to the sides of the window frame A by screws or other fasteners 9.

The outer edges of the rear flanges 6 of the said units B-B are bent inwardly upon the channel strips 8 and thence so formed as to facilitate the attachment of a suitable screen 10 between the side frame units of the said side frame, see Figure 2.

The channel strips 8 of the frame units B-B are formed at their outer faces with circular pits or pockets 11, the inner wall of each of which is formed adjacent the outer edge of the strip with an arcuate slot 12.

Furthermore, between the ends of each of these slots the inner surface and outer wall of the channel strip is formed with an inclined radial slot 13. Rotatably arranged

within each of the channel strip pockets 11 is a pan shaped annulus 14 formed centrally with a cross channel or slot 15 open at its opposite ends and within which is a suitable 5 lining 16' such as rubber or cement. Projecting through and movable within the arcuate slots 12 of the channel strip pockets and attached to the respective annulus 14 is a pin 16 the outer ends of which are associated 10 with a vertical lever 17 arranged between the strips 5 and 8 of the said frame units B. The lowermost pin 16 is of elongated formation and projects through the lowermost annulus 14 as disclosed in Figure 10. This lowermost 15 pin is threaded for receiving a wing nut 18 which when turned inwardly for binding engagement with the adjacent annulus will retain the lever 17 in predetermined position.

The invention further consists of a plurality of glass panels 19, the opposite ends of which are of reduced width for providing tongues 20—20 for arrangement within the slots 15 of opposed annuli within the frame units B—B. The width of these glass panels 25 are such that the adjacent longitudinal edges thereof will have overlapping relation when the annuli are rotated to move their slots to relatively vertical position in which position the sash is entirely closed.

30 However, by releasing the wing nut 18 and drawing downwardly upon the lowermost pin 16 will cause the rotation of the annuli and consequently the rocking of the panels to any desired open position. Whenever it 35 is desired to move any of the glass panels it is only necessary to move the annuli until the cross slots 15 thereof register with the slots 13 of the channel strip 8 whereupon the panels may be slid from position.

40 Arranged beneath the lowermost panel 19 and above the uppermost panel and attached to the main window frame A are cross strips 22—22 for preventing the passage of air, rain and the like through the sash above the upper and lowermost panels when the panels 45 have been moved to closed position.

It will thus be seen that I have provided a highly novel, relatively simple and extremely practical window sash construction that is 50 well adapted for all the purposes heretofore designated, even though I have herein shown and described the invention as consisting of certain detail structural elements it is nevertheless to be understood that some changes 55 may be made therein without affecting the spirit and scope of the appended claims.

Having thus described the invention, what I claim as new is:

1. In a window sash of the character de-

scribed, a pair of spaced parallel frame units, 60 a plurality of longitudinally spaced members rotatably arranged within the inner faces of said frame units, horizontal glass panels arranged at their ends within said members, means whereby all of said members may be 65 simultaneously rotated for moving the panels to open or closed position, the inner faces of said members being cross slotted for receiving the ends of the glass panels and said frame units being formed at their outer edges with 70 slots whereby when the member channels are in alinement with said slots said panels may be removed therefrom.

2. In a window sash of the character de- 75 scribed, a pair of spaced parallel frame units, a plurality of longitudinally spaced members rotatably arranged within the inner faces of said frame units, horizontal glass panels arranged at their ends with said members means whereby all of said members may be simulta- 80 neously rotated for moving the panels to open or closed position, said means consisting of a lever longitudinally movable within each frame unit and connected to said mem- 85 bers by pins projecting through arcuate slots in the inner faces of said frame units, and securing means attached to the lower end of one lever projecting through the inner face of said frame unit in a manner and for the 90 purpose described.

3. In a window sash of the character de- 95 scribed, a pair of spaced parallel frame units, a plurality of longitudinally spaced members rotatably arranged on the inner faces of said frame unit, horizontal transparent panels secured at their ends to said rotatable mem- 100 bers, an elongated member connected to said rotatable member whereby the same may be rotated, a pin projecting from one end of said elongated member and being threaded, a head on the outer end of said pin, said pin adapted to project through one of said rotatable members, and a member threaded thereon for binding engagement against the 105 said rotatable member.

4. In a window sash of the character de- 110 scribed, a pair of spaced parallel frame units, each of said units being formed with longitudinally spaced circular recesses, the inner walls of certain of said recesses being formed with arcuate slots, circular members for rotation in the recesses, transparent panels ar- 115 ranged between opposing rotatable members, and means operable through said slot for rotating said rotatable members.

In testimony whereof I affix my signature.

RICHARD S. KELLY.
